(57) **CLAIM**

The ornamental design for a harness for euphonium musical instrument, as shown and described.

DESCRIPTION

FIG. 1 is a top, plan view of a harness for euphonium musical instrument showing our new design;

FIG. 2 is a bottom plan view thereof;

FIG. 3 is a left side elevational view thereof;

FIG. 4 is an end elevational view thereof;

FIG. 5 is a front, perspective view of a harness for euphonium musical instrument, the design being shown in use;

FIG. 6 is a rear perspective view thereof;

FIG. 7 is a right side perspective view thereof; and,

FIG. 8 is a left side perspective view thereof.

In FIGS. 1-3 of the drawings, the wavy break lines are for ease of illustration only.

In FIGS. 5-8 of the drawings, the broken lines representing a human form and a musical instrument illustrate the design in use and form no part of the claim.
